UNITED STATES PATENT OFFICE.

JOHN MAGEE, OF CHELSEA, ASSIGNOR TO THE NORTON FURNACE CO., OF NORTON, MASSACHUSETTS.

IMPROVEMENT IN HEATERS.

Specification forming part of Letters Patent No. 37,027, dated November 25, 1862.

To all whom it may concern:

Be it known that I, JOHN MAGEE, a citizen of the United States of America, and a resident of Chelsea, in the county of Suffolk and State of Massachusetts, have made a new and useful invention having reference to stoves, as well as hot-air furnaces; and I do hereby declare the same to be fully described in the following specification, and represented in the accompanying drawings, of which—

Figure 1 is a top view, Fig. 2 a side elevation, and Fig. 3 a vertical and transverse section, of the internal parts of a hot-air furnace as provided with my invention, which particularly belongs to hot-air furnaces or stoves whose radiators are furnished with pipes or conduits to extend and convey air through them for the purpose of being warmed or heated.

In the said drawings, A denotes the fire-pot or fuel-chamber as provided with a grate, B, and situated over an ash pit or chamber, C. The said fire-pot A is placed within a radiator or domed chamber, D, having under its bottom a smoke-discharging conduit or trunk, E, which is extended partially around the ash-chamber, and at or near the front part of the furnace may be made to open into a vertical discharge-flue, F. The radiator is to freely communicate with the said conduit E. A series of pipes, G G G G, extend from the vertical sides of the radiator to its top, each of them being arranged within the radiator. To each of these air-conduits there may be another, which may extend beyond the sides of the radiator, as shown at H in the drawings, it being understood that each of these last-named pipes is not only to pass through the air-chamber I and the case or wall thereof, which is to surround the said radiator, but is to open at its lower end into the air outside of such chamber I.

When air-pipes are used within a radiator in manner as described, it has been found very difficult to preserve tight joints at their connections with the top and sides of the radiator, owing to the unequal expansion and contraction of the radiator, and the pipes (caused by heat) either crack in the joints, or breakage of the pipes is apt to ensue, and thereby allow of leakage of more or less smoke or gases into the chamber containing the radiator.

The principal object of my invention is to prevent not only breakage of the air-pipes, but to preserve their joints tight when the stove or furnace may be in use. To accomplish this, I support each of the air-conduits which passes through the radiator by yielding joints arranged at both ends of it, and although the lowermost joint used is what may be termed a "sand joint," the uppermost one is a combination of a sand joint and a fusible-metal joint, such being constructed and arranged substantially in manner and to operate as hereinafter specified. The air from the chamber about the radiator may be caused to pass into the lower ends of the pipes which go through the radiator, and after coursing through them may be discharged into such chamber, such air being heated in its passage through the pipes. I prefer, however, to apply or connect to each of such pipes, and to the lower end thereof, another pipe to lead through the air-chamber, and so as to convey into the first-mentioned pipe air from without the air-chamber, for I have found that such air on entering the radiator-pipe will be cooler than air taken from the air-chamber, and, as a necessary result, will operate to better advantage in preventing the radiator-pipe from extending lengthwise. As the radiator-pipes will expand quicker than the radiator at the period of first making a fire in the furnace, it becomes desirable to check the said expansion to an extent which will cause it to comport with that of the radiator. Now, this result may be approximated, if not entirely effected, by introducing into the radiator-pipes air from without the hot-air chamber. The lower end of each radiator-pipe is connected with the side of the radiator by an ordinary sand joint, K, which consists not only of a short pipe, a, but of a concentric box, b, the latter containing sand. The lower end of the radiator-pipe shuts over the pipe a, enters the box b, and is to be covered by a mass of sand or some equivalent placed therein. The short pipe a may open either into the air-chamber about the radiator or into an air pipe or conduit, H. The upper joint of each of the pipes G is a compound one—that is to say, it is composed of a fusible-metal joint and what is termed a "sand joint," which are constructed in the following manner: The pipe G has two bowls, c d, cast

around or applied about it, one of them being placed within the other. A conical or cylindrical tube, *e*, extends from the top *g* down into the bowl *c*. Another such pipe, *f*, also projects down from the said top *g* and into the bowl *d*. Both pipes *G* and *f* open out of the top of the radiator. The bowl *d* is to contain a mass of lead or other metal easily rendered fusible, or of being melted by heat of the pipe *G* while the furnace may be in operation. The bowl *c* is to contain sand, *i*, or some other suitable equivalent, which may be carried up to such height as to cover the lead, *h*, in order to protect it from oxidation. While the furnace may be in operation the lead will be melted, and as the partition-pipe *f* dips into it such lead will preserve a tight joint. The pipe or part *e* is not essential to my invention, but is a useful auxiliary, as it contributes, with the sand, to preserve a tight joint. The part *f*, extending into the sand as well as into the lead, aids in making a sand joint as well as a fusible-metal joint. The compound joint is a yielding one, as it will not only allow the pipe *G* to accommodate itself to the metal, but to the lateral expansions and contractions of the radiator.

The lower joint of the pipe will allow of longitudinal as well as lateral movements of the pipe.

It will be seen from the above that the lower end of the air-pipe is not fastened to the radiator by screw-bolts, so as to be immovable, but in reality is in no respect fastened thereto. My mode of applying each of the air-pipes to the radiator—viz., by yielding joints, both at top and bottom—it will thus be seen, is one of great utility.

I claim—

1. Supporting each of the air-conduits *G* by yielding joints, substantially as set forth, arranged at both ends of the same, and with respect to the top and side of the radiator; as specified.

2. The combination of the sand and fusible-metal joints, constructed and arranged substantially in manner and so as to operate together as specified.

JOHN MAGEE.
